(57) **CLAIM**

The ornamental design for a shoe box, as shown and described.

DESCRIPTION

FIG. 1 is a perspective view of our new design;

FIG. 2 is a perspective view of our new design, shown in a partially open condition;

FIG. 3 is a top plan view of FIG. 1;

FIG. 4 is a left side elevational view of FIG. 1; and,

FIG. 5 is a front elevational view of FIG. 1.

The broken line showing of a mount illustrates environment only and forms no part of the claimed design.
